APPARATUS FOR TIMING RELAY OPERATIONS

Harold F. Blair, Chicago, Ill., assignor to Western Electric Company, Incorporated, New York, N. Y., a corporation of New York

Application January 9, 1948, Serial No. 1,387

6 Claims. (Cl. 175—183)

1

This invention relates to electrical circuits for measuring time intervals and more particularly to electronic timing circuits for measuring the time intervals of operations of electrical relays.

It is an object of this invention to provide a new and efficient electrical timing circuit for measuring the time required for electrical relays to perform their functions.

In accordance with one embodiment of this invention, a timer control circuit includes a triode vacuum tube connected in series with the operating coil of a timer and in series with a gas filled electronic tube together with a power supply for energizing the timer coil and operating the tubes. The current through the series circuit of the coil, the vacuum tube and the gas tube is controlled through the operation of the relay under test and its associated contacts. The vacuum tube is first placed in a state in which it will conduct when the gas tube is fired. The normally quiescent gas tube is fired at the start of that part of the relay operation which is to be timed. Firing of the gas tube causes current to flow through the series circuit of the gas tube, the vacuum tube and the timer coil thereby starting the timer. At the end of that part of the operation of the relay which is being timed, the action of the relay applies a blocking bias to the control grid of the vacuum tube cutting off the current flow through the series circuit including the coil of the timer thus stopping the timer.

A complete understanding of this invention will be had by reference to the following detailed specification taken in conjunction with the single figure drawing which illustrates diagrammatically one embodiment of the invention.

As shown in the drawing, the apparatus is provided with an electronic vacuum tube 10 and an electronic gas-filled tube 11 connected in series with an operating or control coil 12 of a timer 13. This series combination is connected through a resistor 14 to a suitable power supply 15 which may be a battery, the negative end of the battery being connected to the cathode 19 of the tube 11 and the positive end of the battery being connected through the resistor 14 to one end of the coil 12. The tube 10 is provided with an anode 20, a control grid 21 and a cathode 22, and the tube 11 is provided with an anode 23, a shield grid 24 and a control grid 25. In the series arrangement, one end of the coil 12 is connected to the anode 20, and the cathode 22 is connected to the anode 23. The shield grid 24 is tied to the cathode 19.

2

In case there is a difference between the start time and the stop time of the timer, a compensating circuit 30 may be provided to make the starting time of the timer conform with the stop time of the timer. The circuit 30 comprises a variable resistor 31 connectable in series with a condenser 32 through a single pole double throw switch 33, which switch also may be operated to discharge the condenser 32 through a shunting resistor 34. The compensating circuit 30 is connected across the tube 10 and the operating coil 12 and in conjunction with resistor 14 has the effect of preventing a sudden current build up in the coil 12. The resistor 31 may be varied to change the current build-up time in the coil, thus to change the starting time of the timer 13.

It will be seen that when both the vacuum tube 10 and the gas tube 11 are in a conducting state current will flow through the operating coil 12 thereby to start the timer. It will also be apparent that there will be no current flow through the coil 12 if either of the tubes 10 or 11 is in a non-conducting state. If it is assumed that both tubes are conducting and that current is flowing through the coil 12, a sudden blocking of the tube 10 by means of a cut off biasing voltage applied to the grid 21 will suddenly cut off the current through the coil 12 and thereby stop the timer.

If the tube 11 is in a quiescent state and the grid 21 of the tube 10 is properly biased, the timer 13 may be started by the firing of the tube 11 upon application of the proper voltages, and as pointed out before the timer may be stopped by suddenly blocking the tube 10. In the specific embodiment described herein the tube 10 will conduct current when its grid 21 is at the same potential as its cathode 22 and the tube 11 has been fired, and the tube 10 may be blocked by applying to its grid 21 a cut off biasing voltage obtained from the negative end of a battery 36 whose positive end is connected to the negative end of the battery 15 and to the cathode 19 of the tube 11.

These methods of starting and stopping the timer may be employed to time the various operations of relays having either make or break contacts. To effect the control of the timing circuit by the relay being tested, the control portions of the tubes 10 and 11 are connected to a relay 40 under test and its associated contacts 41 through a five pole double throw switch 42 and a single pole double throw switch 43. The switch 42 is provided with poles 50, 51, 52, 53 and 54. The poles of the switch 42 are engageable

with contacts as follows: pole 50 with contacts 60 and 61, pole 51 with contacts 62 and 63, pole 52 with contacts 64 and 65, pole 53 with contacts 70 and 71, and pole 54 with contacts 72 and 73.

When the switch 42 is operated to the left as shown in the drawing, the following circuit connections are made: The negative end of the battery 36 is connected through the contacts 69, the pole 50 and a resistor 75 to the grid 21 to apply a cut off bias on that grid. At the same time, the grid 21 is also connected to a test terminal 80 to which one of the contacts of the relay under test may be connected, and the cathode 22 is connected through the contacts 72 and pole 54 to a test terminal 81 to which the other contact of the relay under test may be connected. The resistor 75 allows the negative end of the battery 36 or the cathode 22 to be connected to the grid without shorting the battery 36. The operating coil 82 of the relay 40 under test is connected to two test terminals 83 and 84 which are connectable through switches 85 and 86 to a battery 90 which serves to energize the operating coil 82 and also, as hereinafter described, to apply a blocking voltage to the grid 25. The control grid 25 of the gas tube 11 is connected to a resistor 91 which is connectable by means of switch 43 to either the terminal 83 or the terminal 84. Resistor 91 should have a relatively high resistance to prevent the gas tube 11 from altering the characteristics of the relay coil 82 when the coil is connected across portions of the gas tube during the release time tests hereinafter described.

Timing release time of make contacts of a relay

All the switches in the circuit are shown in the drawing in a position which prepares the circuit for timing the release time of the make contacts of a relay under test. Such a relay is connected in the circuit as the relay 40, its operating coil 82 being connected to the test terminals 83 and 84 and its make contacts 41 connected to the test terminals 80 and 81.

In the state in which the apparatus appears in the drawing the tube 10 is blocked with a high negative bias on the grid 21 thus preventing the tube 11 from being fired. As soon as the switch 85 is closed, a negative blocking bias is applied to the grid 25 of the tube 11 from the battery 90 through switches 85 and 43. At the same time the coil 82 of the relay 40 under test is energized to close the contacts 41 thereby connecting the grid 21 to the cathode 22 of the tube 10 thus preparing the tube 10 for current conduction.

After the relay coil 82 has been held energized for a predetermined time, the switch 85 is opened to cut off the current through the coil 82. At the same time the negative blocking bias is removed from the grid 25 of the tube 11, and the grid 25 being connected to the anode 23 through the switch 43, the coil 82 and the switch 86, it will be at the same potential as the anode and the tube 11 will be fired. This will cause an initially high charging current to flow through the condenser 32 and the resistors 31 and 14, causing an initially high voltage drop to appear across the resistor 14 and correspondingly low initial current to flow through the coil 12 which current will increase as the condenser 32 charges up. As soon as the condenser is charged, the current through the coil 12 will be high enough to start the timer 13.

When the relay contacts 41 are released, they

10
5

open the circuit between the cathode 22 and the grid 21 thus permitting the bias voltage from the battery 36 to block the tube 10 and cut off the current through the timer coil 12, thereby stopping the timer 13. Thus it will be seen that the release time of the relay will be indicated on the timer.

Timing the operate time of make contacts of a relay

In order to prepare the apparatus for timing, the operate time of the make contacts 41 of the relay 40, the switch 43 is operated to connect the grid 25 to the test terminal 84, the switch 86 is opened and the switch 85 is closed. In addition the five poles 50, 51, 52, 53 and 54 of the switch 42 are operated to the right to engage the contacts 61, 63, 65, 71 and 73, respectively. This connects the negative end of the battery 36 to the test terminal 81, connects the test terminal 80 to the grid 21 of the tube 10, and connects the resistor 75 between the grid 21 of the cathode 22 of the tube 10.

At this stage it will be seen that the tube 10 is prepared to conduct current since its grid and its cathode are at the same potential. The tube 11 is blocked because its grid 25 is tied to the negative end of the battery 90 through switch 43, relay coil 82 and the closed switch 85.

The timing test is initiated by closing the switch 86 which simultaneously connects battery 90 to the operating coil 82 of the relay 40 and connects the grid 25 of the tube 11 to the anode 23 of the tube 11 to fire the tube 11. As hereinbefore described, current will flow through the series circuit of the tubes 10 and 11 and the coil 12 thereby starting the timer 13. When the contacts 41 close, the negative end of the battery 36 is connected through the switch pole 50, contact 61, switch pole 54, contact 73 and the relay contacts 41 to the grid 21 of the tube 10 thereby blocking the tube 10 and stopping the timer 13. The indication on the timer will be the operate or make time of the make contacts 41 of the relay 40.

Timing of the operate time of break contacts of a relay

To time the operate time of a pair of break contacts 92 of the relay 40, switch 86 must be opened, switch 85 should be closed, switch 43 is operated to connect the grid 25 to the test terminal 84, and the poles 50, 51, 52, 53 and 54 of the switch 42 are operated to the left as they appear in the drawing. The contacts 41 are disconnected from the terminals 80 and 81, and the contacts 92 are connected to the terminals 80 and 81. With the switches in the positions just described the negative end of the battery 36 will be connected to the grid 21 of the tube 10 through the resistor 75 and the grid 21 will be tied to the cathode 22 of the tube 10 through the closed contacts 92 so that the grid 21 and the cathode 22 will be at the same potential thus readying the tube 10 to conduct current as soon as the tube 11 is fired. Tube 11 is quiescent because its grid 25 is connected through the switch 43, the relay coil 82 and the closed switch 85 to the negative end of the battery 90.

To time the operation of the break contacts 92, the switch 86 is closed thereby connecting the positive end of the battery 90 simultaneously to the relay coil 82 and the grid 25 of the tube 11 which fires and causes current to flow through the tube 10 and the timer coil 12 to start the timer 13. As soon as the contacts 92 break open,

the circuit between the cathode 22 and the grid 21 of the tube 10 is broken thereby blocking the tube 10 and stopping the timer 13. The reading on the timer 13 will be the operate or break time of the break contacts 92 associated with the relay 40.

*Timing the release time of break contacts
of a relay*

In order to prepare the circuit to time the release time of break contacts 92, the switch 85 is opened, the switch 86 is closed, the switch 43 is operated upward to connect the grid 25 of the tube 11 to the test terminal 83 and the switch poles 50, 51, 52, 53 and 54 of the switch 42 are operated to the right to engage the contacts 61, 63, 65, 71 and 73, respectively. With the switch 42 in this position the grid 21 is tied through the resistor 75 to the cathode 22 of the tube 10 and the grid 21 is connected through the contacts 92 to the negative end of the battery 36 thus locking the tube 10.

The test is started by closing switch 85 to simultaneously connect the battery 90 to the operating coil 82 of the relay 40 and to connect the negative end of the battery 90 to the grid 25 of the tube 11 to prevent its firing.

The relay coil 82 being connected to the battery 90, it will be energized to open the break contacts 92 thereby removing the blocking bias of the battery 36 from the grid 21 of the tube 10 and preparing the tube 10 to conduct current. After the relay coil 82 is "soaked" the switch 85 is opened to disconnect the battery 90 from the relay coil 82 and to remove the negative blocking bias from the grid 25 of the tube 11. The grid 25 being connected to the anode 23 through the switch 43, relay coil 82 and the switch 86, the tube 11 will be fired and will conduct current causing current to flow through the tube 10 and through the timer coil 12 thus starting the timer 13. When the contacts 92 are released they will close to connect the negative end of the battery 36 to the grid 21 of the tube 10 thereby blocking the current through the tube 10 and stopping the timer 13. The timer will then indicate the release time of the break contacts 92.

If the timer 13 is of the type that may be inherently compensated or has no differential between its start and stop inertias when connected in the present apparatus, the compensating circuit 30 comprising the resistors 31 and 14 and the condenser 32 is not essential to the operation of the apparatus described herein.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for timing relay operations, said apparatus comprising a first electronic tube, a second electronic tube connected in series with the first tube, each of said tubes having an anode, a control grid and a cathode, the anode of the second tube being coupled to the cathode of the first tube to receive operative anode voltage only through the first tube, a source of unidirectional anode voltage having its positive side coupled to the anode of the first tube and its negative side coupled to the cathode of the second tube, an electric timer control operable to start and stop a timer in response to anode cur-

rent flow in said tube circuit, a relay with switching contacts controlled thereby, means for energizing the relay, means for applying a blocking bias voltage to the control grid of the second tube when the relay is energized, means for applying a firing voltage to the control grid of the second tube when the relay is deenergized, means coupled to the control grid of the first tube and through said contacts for applying a conducting bias voltage to the control grid of the first tube in response to the operation of said contacts, and means coupled to the control grid of the first tube and to said contacts for applying a blocking bias voltage to the control grid of the first tube when said contacts are released.

2. An apparatus for timing relay operations, said apparatus comprising an electronic vacuum tube, an electronic gas tube, each of said tubes having an anode, a control grid and a cathode, 20 said tubes being connected in series with each other to receive operative anode voltage only through each other, an electric timer control in series with the anode current path of the vacuum tube and operable to start and stop a timer in response to anode current in said tube, a source of unidirectional anode voltage having its positive side coupled to the anode of the vacuum tube and its negative side coupled to the cathode of the gas tube, a relay with switching contacts controlled thereby, means for energizing the relay, 25 means for applying a blocking bias voltage to the control grid of the gas tube when the relay is energized, means for applying a firing voltage to the control grid of the gas tube when the relay is deenergized, means coupled to the control grid of the vacuum tube through said contacts for applying a conducting bias voltage to the control grid of the vacuum tube in response to the operation of said contacts, and means coupled to 30 the control grid of the vacuum tube and to said contacts for applying a blocking bias voltage to the control grid of the vacuum tube when said contacts are released.

3. An apparatus for timing relay operations, 45 said apparatus comprising an electronic vacuum tube, an electronic gas tube connected in series with the vacuum tube, each of said tubes having an anode, a control grid and a cathode, the anode of the gas tube being coupled to the cathode of the vacuum tube to receive operative anode voltage only through the vacuum tube, a source of unidirectional anode voltage having its positive side coupled to the anode of the vacuum tube and its negative side coupled to 50 the cathode of the gas tube, an electric timer control operable to start and stop a timer in response to anode current flow in said tube circuit, a relay with switching contacts controlled thereby, means for energizing the relay, means for applying a blocking bias voltage to the control grid of the gas tube when the relay is energized, 55 means for applying a firing voltage to the control grid of the gas tube when the relay is deenergized, means coupled to the control grid of the gas tube through said contacts for applying a conducting bias voltage to the control grid of the vacuum tube in response to the operation of said contacts, and means coupled to the control grid of the vacuum tube and to 60 said contacts for applying a blocking bias voltage to the control grid of the vacuum tube when said contacts are released.

4. An apparatus for timing relay operations, 65 said apparatus comprising an electronic vacuum tube, an electronic gas tube, each of said tubes

having an anode, a control grid and a cathode, said tubes being connected in series with each other to receive operative anode voltage only through each other, an electric timer control in series with the anode current path of the vacuum tube and operable to start and stop a timer in response to anode current in said tube, a source of unidirectional anode voltage having its positive side coupled to the anode of the vacuum tube and its negative side coupled to the cathode of the gas tube, a relay with switching contacts controlled thereby, means for energizing the relay, means for applying a blocking bias voltage to the control grid of the gas tube when the relay is deenergized, means for applying a firing voltage to the control grid of the gas tube when the relay is energized, means coupled to said contacts and to the control grid of the vacuum tube for applying a conducting bias voltage on the control grid of the vacuum tube when the contacts are unoperated, and means coupled to said contacts and to the control grid of the vacuum tube for applying a blocking bias to the control grid of the vacuum tube in response to the operation of the contacts.

5. An apparatus for timing relay operations, said apparatus comprising an electronic vacuum tube, an electronic gas tube connected in series with the vacuum tube, each of said tubes having an anode, a control grid and a cathode, the anode of the gas tube being coupled to the cathode of the vacuum tube to receive operative anode voltage only through the vacuum tube, a source of unidirectional anode voltage having its positive side coupled to the anode of the vacuum tube and its negative side coupled to the cathode of the gas tube, an electric timer control operable to start and stop a timer in response to anode current flow in said tube circuit, a relay with switching contacts controlled thereby, means for energizing the relay, means for applying a blocking bias voltage to the control grid of the gas tube when the relay is deenergized, means for applying a firing voltage to the control grid of the gas tube when the relay is energized, means coupled to said contacts and to the control grid of the vacuum tube for applying a conducting bias voltage on the control grid of the vacuum tube when the contacts are unoperated, and means coupled to said contacts and to the control grid of the vacuum tube for applying a blocking bias to the control grid of the vacuum tube in response to the operation of the contacts.

6. An apparatus for timing relay operations, said apparatus comprising a first electronic tube, a second electronic tube, each of said tubes having an anode, a control grid and a cathode, said tubes being connected in series with each other to receive operative anode voltage only through each other, a source of unidirectional anode voltage connected across said series circuit of the tubes, an electric timer control operable to start and stop a timer in response to anode current flow in said tube circuit, a relay with switching contacts controlled thereby, means for energizing the relay, means for applying a blocking bias voltage to the control grid of the second tube when the relay is deenergized, means for applying a firing voltage to the control grid of the second tube when the relay is energized, means coupled to said contacts and to the control grid of the first tube for applying a conducting bias voltage on the control grid of the first tube when the contacts are unoperated, means coupled to said contacts and to the control grid of the first tube for applying a blocking bias to the control grid of the first tube in response to the operation of the contact, and means for controlling the build up of current through said timer control, last said means comprising a resistor-condenser charging circuit connected in parallel with said timer control.

control grid of the vacuum tube when the contacts are unoperated, and means coupled to said contacts and to the control grid of the vacuum tube for applying a blocking bias to the control grid of the vacuum tube in response to the operation of the contacts.

10. An apparatus for timing relay operations, said apparatus comprising a first electronic tube, a second electronic tube, each of said tubes having an anode, a control grid and a cathode, said tubes being connected in series with each other to receive operative anode voltage only through each other, a source of unidirectional anode voltage connected across said series circuit of the tubes, an electric timer control operable to start and stop a timer in response to anode current flow in said tube circuit, a relay with switching contacts controlled thereby, means for energizing the relay, means for applying a blocking bias voltage to the control grid of the second tube when the relay is deenergized, means for applying a firing voltage to the control grid of the second tube when the relay is energized, means coupled to said contacts and to the control grid of the first tube for applying a conducting bias voltage on the control grid of the first tube when the contacts are unoperated, means coupled to said contacts and to the control grid of the first tube for applying a blocking bias to the control grid of the first tube in response to the operation of the contact, and means for controlling the build up of current through said timer control, last said means comprising a resistor-condenser charging circuit connected in parallel with said timer control.
